CLAIM

We claim the ornamental design for a grooming tool, as shown and described.

DESCRIPTION

FIG. 1 is a perspective view of a grooming tool of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is an exploded perspective view thereof.

The broken lines depict exemplary environment and components for purposes of illustration and form no part of the design claim.

1 Claim, 7 Drawing Sheets
